UNITED STATES PATENT OFFICE.

JEROME WHEELOCK, OF WORCESTER, MASSACHUSETTS.

OPERATING-LEVER FOR PUMPING MACHINERY.

SPECIFICATION forming part of Letters Patent No. 349,551, dated September 21, 1886.

Application filed June 2, 1886. Serial No. 203,936. (No model.)

To all whom it may concern:

Be it known that I, JEROME WHEELOCK, of Worcester, in the county of Worcester and Commonwealth of Massachusetts, have invented new and useful Improvements in Operating-Levers for Pumping Machinery, of which the following, in connection with the accompanying drawings, is a specification, like letters representing like parts.

10 My present invention relates to operating-levers for reciprocating pumps, the pistons of which are propelled through connecting-rods attached to a reciprocating part of machinery of any description by any ordinary mechanism, and has for its object to give an easy and yielding stroke to the piston which forces the liquid through the discharge-pipe.

Furthermore, my invention consists of the improved construction of said lever combining two separate levers into one and applying springs for an easy adjustment.

As is well known to those skilled in the art, there is always in the cylinders of direct-acting pumps a certain amount of pressure 25 which is created by the resistance of the fluid crowding through small openings in a large quantity. This is particularly the case with those pumps whose pistons are traveling rapidly, necessitating the displacement of a large 30 amount of water or any other liquid in a very short time, so that when the piston is solidly connected to any reciprocating mechanism which has a positive movement there is always danger of breaking a part of the pump 35 or its connection with the driving power should the resistance be so great as to prevent the piston from performing its duty.

In view of this fact my invention is especially adapted for pumps of the above-mentioned variety, as illustrated in the accompanying drawings, in which—

Figure 1 represents a pump connected by means of my improved lever and a link with the cross-head of a steam-engine. Fig. 2 is a 45 front view of my improved lever, illustrating its action in case of too much compression in the cylinder of the pump; and Figs. 3 and 4 in several views show my improved lever in detail, the main acting parts being separated.

50 Referring to the drawings, A is a pump-cylinder having a piston and piston-rod, a,

attached at its forward end to a cross-head, b, sliding on guide-bar c, all of common construction. To the cross-head b a coupling-rod, B, is attached, which connects at d with the novel 55 operating-lever C, as fully shown in Fig. 1.

The lever C is pivoted at its lower end, e, in a bearing which is firmly bolted to the foundation, while its upper end is directly connected by means of a link, D, to the cross-head of an engine. It will be seen that if the cross-head should move forward, the piston of the pump would move in the same direction, the travel of the latter, however, being shorter than that of the former on account of the difference in the distances of the points f and d from the fulcrum e.

As my present invention the lever C consists of the two parts C' and C'', which are cast or made separately to be afterward united by 70 a pin or bolt at g, which serves as a pivot for the small arm C'', which is adjustably held in proper position by means of springs h h resting against the wings i i at the lower end of the lever C and firmly attached to the swing- 75 ing end of the arm C'.

In order to secure a guide for the arm C'' at its lower or loose end, I provide the wings i of the lever C with holes i', as shown in Fig. 3, through which and the springs h h a bolt, j, 80 is drawn and secured by nuts k k. (Shown in Figs. 1 and 2.)

To enable the arm C'' to properly swing or adjust itself to the extent allowed by the springs, the hole in the loose end of the lever 85 through which the bolt j passes is elongated, as especially illustrated in Fig. 4. As previously stated, the coupling-rod B, connecting the lever C with the pump-piston, is attached to the former at the point d, and the effect and 90 working of my improved lever will be seen in Fig. 2, where the upper end is represented as being moved by power in the direction of the arrow. The resistance which the piston in the pump meets with is transferred to the arm 95 C'', which yields after a certain amount of pressure has been attained, and then takes its normal position again, the springs h h operating to that purpose. By these means the surplus strain is practically taken off the operating 100 parts, allowing the machinery to run smoothly without being liable to break either cylinder-

head, bolts, pins, piston, connecting-rod, cross-head, besides totally avoiding the "water-hammer."

Since there are a great many different ways 5 of moving the lever C in the desired manner, I have chosen merely one to illustrate the connection between power and pump by means of my improved operating-lever, the ways of reciprocating the upper end of the same being optional; but

What I claim as new and my invention, and desire to secure by Letters Patent, is—

In an operating-lever for pumping machinery, the combination, with a lever pivoted at one end and provided with lugs or wings 15 and springs resting against the same, of an arm connected with the pump and pivoted to said lever, all operating as and for the purpose specified.

JEROME WHEELOCK.
